UNITED STATES PATENT OFFICE.

ROY V. McNABB, OF RARDIN, ILLINOIS.

HOG RINGER.

Application filed April 6, 1928. Serial No. 267,932.

The present invention relates to improvements in hog ringing implements, and has for its principal object to provide a device of this character that is adapted for applying rings in the noses of hogs or other animals.

One of the important objects of the present invention is to provide a hog ringer having the magazine adapted to contain a plurality of open rings, means being provided for automatically feeding the rings to a pair of co-acting jaws, one at a time, so that the implement can be used to successively attach the rings to a number of hogs in an expeditious manner.

A further object of the invention is to provide a hog ringer of the above mentioned character, which would at all times be positive and efficient in operation, the same being further simple in construction, inexpensive, strong and durable, and further well adapted to the purpose for which it is designed.

Another object of the invention resides in the provision of a ring holding magazine that is of such construction as to be capable of adjustment to accommodate rings of different sizes.

Other objects of the invention will become apparent as the nature of the invention proceeds and when taken in connection with the accompanying drawing.

In the accompanying drawings, forming a part of this application and in which like numerals designate like parts throughout the several views:

Figure 1 is a plan view of the hog ringer embodying my invention.

Figure 2 is a side elevation thereof.

Figure 3 is a front elevation.

Figure 4 is a rear elevation of the magazine and the co-acting jaws, the latter being shown in section.

Figure 5 is a sectional view, taken approximately on the line 5-5 of Figure 3, looking upwardly.

Figure 6 is a vertical sectional view, taken approximately on the line 6-6 of Figure 3, and

Figure 7 is a detail perspective view of one of the rings used in connection with the device.

In the drawings, wherein for the purpose of illustration is shown the preferred embodiment of my invention, the numeral 1

designates generally my improved hog ringer, the same comprising a pair of cross handles 2 and 3 respectively, that are pivotally connected together, as at 4, the pivoted ends of the handles merging into a pair of 60 co-acting jaw members 5 and 6 respectively, that are of an enlarged nature, and these jaws are provided with oppositely disposed ring receiving cavities, in the proximate faces and at the inner edges thereof, as 65 designated by the numerals 7 and 8, respectively.

A set screw or thumb screw 9 is threaded through a transverse opening provided therefor in the handle 2, adjacent the pivoted 70 end thereof for engagement with the complementary handle 3, for limiting the swinging movement of said handle as will be readily apparent from the construction shown in Figure 1, and the purpose of this thumb 75 screw will be hereinafter more fully described.

The invention further comprehends the provision of a ring receiving magazine which is designated generally by the numeral 10. This magazine is of an adjustable 80 nature to accommodate rings of different sizes, and to this end, the magazine comprises a pair of transversely curved sections 11 and 12 respectively, that are open at their inner opposed faces. The back portion of the section 11 is formed with a plate like extension 13 that extends across the back portion of the complementary section 12 and the free edge portion of this plate like extension is formed with the slots 14 that extend inwardly from the free side edge of said extension and through which slots are disposed the bolts 15 that project through the rear wall of the section 12. Suitable nuts 85 16 are threaded on the rear ends of the bolts for engagement with the outer face of the plate like extension 13, whereby said sections are adjustably secured together, in spaced 90 relation, to receive a plurality of hog rings of a particular size.

The upper end of each section is closed, while the lower end is open.

A laterally extending attaching lug 17 is formed on the lower end of the section 11, 105 whereby the magazine is rigidly secured to the jaw 6, by the bolt 18, and the magazine will thus be disposed at right angles with respect to the jaws shown in the drawings.

The magazine is adapted to be filled with a number of rings, one of which is shown at 19, with reference more particularly to Figure 7, and for the purpose of feeding the 5 rings downwardly into position in the ring receiving cavities formed in the cooperating jaws 5 and 6, there is provided a pair of followers 20, shaped to conform to the contour of the transversely curved section of 10 the magazine 10 and these followers are secured on the lower end of the pair of plunger rods 21, that extend upwardly in the respective sections of the magazine through the closed upper ends thereof. The 15 upper ends of these plunger rods are threaded, for receiving thereon lugs 22, that engage with the top of the magazine to limit the downward sliding movement of the plunger rods and the followers secured on 20 the lower end thereof.

A coil spring 23 encircles each of the plunger rods for disposition between the closed upper end of the respective section of the magazine and the adjacent follower, 25 whereby to normally urge the plunger rods downwardly and to exert a downward pressure on the stack of rings placed in the magazine.

An additional coil spring 24 interconnects 30 the lower ends of the vertically disposed coil springs 23, in the manner as clearly shown in Figure 3, and this transversely disposed coil spring exerts an outward pressure on the lower end of the plunger rod to maintain the followers in their proper position in 35 the respective sections of the magazine.

In Figure 3 of the drawings, there is clearly shown the manner in which the followers feed or urge one of the rings 19 into position for rest in the cavities 7 and 8, so that 40 when the free ends of the handles 2 and 3 are grasped and urged inwardly, said jaws 5 and 6 will cooperate to insert the open ring in the nose of the animal and the free ends 45 of the ring will be brought together to close said ring and thereby positively securing the ring in the animal's nose.

The thumb screw 9 will limit the inward movement of the handles with respect to 50 each other, so that the jaws 5 and 6 will be limited in their movement toward each other, so that said jaws will not cause any injury to the animal, while the implement is in use. By attaching the magazine to one of 55 the jaws, the other jaw is free to operate underneath the other side of the magazine.

The magazine may be refilled by forcing 60 the followers 20 upwardly against the tension of the coil springs 23, that encircle the plunger rods and in this manner the implement can be used to successively apply or attach the rings to a number of hogs, thus saving considerable time and labor.

A hog ringer of the above mentioned 65 character will, at all times, be positive and

efficient in its operation, and due to its simplicity, the parts can be readily and easily adjusted.

While I have shown the preferred embodiment of my invention, it is to be understood that various changes in the size, shape, and arrangement of parts may be resorted to, without departing from the spirit of the invention and the scope of the appended claims.

Having thus described my invention, what I claim as new is:

1. In a hog ringer, a pair of pivotally connected handles, co-acting jaws formed on the pivoted ends of the handles, said jaws being provided with ring receiving cavities in the opposed inner faces thereof, a ring receiving magazine open at its lower end for disposition above the said cavities, said magazine being adjustable to accommodate rings of different sizes, and means for feeding the rings in the magazine to the cavities of the jaws, said magazine comprising a pair of complementary sections open at their inner opposed sides, an extension formed on the rear side of one section, and complementary means between the rear side of the other section and said extension for adjustably securing said sections in spaced relation with respect to each other.

2. In a hog ringer, a pair of pivotally connected handles, co-acting jaws formed on the pivoted ends of the handles, said jaws being provided with ring receiving cavities in the opposed inner faces thereof, a ring receiving magazine open at its lower end for disposition above the said cavities, said magazine being adjustable to accommodate rings of different sizes, means for feeding the rings in the magazine to the cavities of the jaws, said magazine comprising a pair of complementary sections open at their inner opposed sides, an extension formed on the rear side of one section, and complementary means between the rear side of the other section and said extension for adjustably securing said sections in spaced relation with respect to each other, and a lug extending laterally from the lower end of one section 110 for attachment to the adjacent jaw.

3. In a hog ringer, a pair of pivotally connected handles, co-acting jaws formed on the pivoted ends of the handles, said jaws being provided with ring receiving cavities in the opposed inner faces thereof, a ring receiving magazine open at its lower end for disposition above the said cavities, said magazine being adjustable to accommodate rings of different sizes, means for feeding the rings in the magazine to the cavities of the jaws, said magazine comprising a pair of complementary sections open at their inner opposed sides, an extension formed on the rear side of one section, and complementary 125

means between the rear side of the other section and said extension for adjustably securing said sections in spaced relation with respect to each other, said last men-

5 tioned means comprising bolts extending through the rear wall of the last mentioned section, the free end of said extension being

slotted to accommodate the threaded ends of the bolts, and nuts threaded on said bolts for engagement with the outer face of the 10 extension.

In testimony whereof I affix my signature.

ROY V. McNABB.
